UNITED STATES PATENT OFFICE

126,698

DESIGN FOR A ROADWAY INSTRUCTION DEVICE

Wayne B. Detrick, Winterset, Iowa

Application July 29, 1940, Serial No. 94,002

Term of patent 3½ years

To all whom it may concern:

Be it known that I, Wayne B. Detrick, a citizen of the United States and a resident of Winterset, in the county of Madison and State of Iowa, have invented a new, original, and ornamental Design for a Roadway Instruction Device, of which the following is a specification, reference being had to the accompanying drawing, forming part hereof, in which the figure is a perspective view of a roadway instruction device showing my new design.

I claim:

The ornamental design for a roadway instruction device, as shown.

WAYNE B. DETRICK.
